UNITED STATES PATENT OFFICE

101,558

DESIGN FOR A PANEL

Leo W. Rose, Dover, Ohio, assignor to The Reeves
Manufacturing Company, Dover, Ohio, a corporation of Ohio

Application August 12, 1936, Serial No. 64,376

Term of patent 14 years

To all whom it may concern:

Be it known that I, Leo W. Rose, a citizen of the United States, residing at Dover, in the county of Tuscarawas and State of Ohio, have invented a new, original, and ornamental Design for a Panel, of which the following is a specification, reference being had to the accompanying drawing, forming part thereof.

The figure is a plan view of a panel, showing my new design.

I claim:

The ornamental design for a panel, as shown.

LEO W. ROSE.
